Primary Examiner — Mitchell I. Siegel*(74) Attorney, Agent, or Firm* — Klarquist Sparkman, LLP(57) **CLAIM**

We claim the ornamental design for a golf club head, as shown and described.

DESCRIPTION

FIG. 1 is a perspective view of a golf club head, as viewed from above, front and one side thereof.

FIG. 2 is a front elevation view of the golf club head of FIG. 1.

FIG. 3 is a perspective view of the golf club head of FIG. 1, as viewed from below, rear and one side thereof.

FIG. 4 is a bottom plan view of the golf club head of FIG. 1; and,

FIG. 5 is a side elevation view of a toe side of the golf club head of FIG. 1.

The broken lines in the drawings are for purposes of illustrating portions of the design that form no part of the present claimed design.
